UNITED STATES PATENT OFFICE.

JOHN AUGUSTUS ESSBERGER, OF BERLIN-SCHÖNEBERG, GERMANY.

ELECTRICALLY-OPERATED DRIVING-GEAR.

1,022,666.

Specification of Letters Patent. Patented Apr. 9, 1912.

Application filed October 4, 1910. Serial No. 535,294.

To all whom it may concern:

Be it known that I, JOHN AUGUSTUS ESSBERGER, a subject of the Emperor of Germany; residing at 19 Münchenerstrasse, Berlin-Schöneberg, Germany, have invented certain new and useful Improvements Relating to Electrically-Operated Driving-Gear, of which the following is a specification, reference being had therein to the accompanying drawing.

This invention relates to electrically operated driving gear and its object is to provide simple means by which a very wide range of speeds may be obtained in machines and the transference from one speed to another may be effected without shock to the parts.

Hitherto the electrical driving of such rotary machines as cranes, gun setting gear, paper machines, printing machines, train cars and so on has been associated with the use of large and expensive regulating resistances and starting gear when it was necessary to obtain a fine graduation of the speed within wide limits.

According to the present invention electric motors are mechanically coupled by a gear whose ratio is approximately the same as the speed range of the motors, while the motors have approximately the same speed range. By speed range is meant the ratio of the maximum to the minimum velocity for which the motors are wound; in some cases two or more controllable motors whose speed ranges progress in series may be directly connected; and these two methods may if desired be combined.

The following description will enable the main idea of this invention to be readily understood and will also serve to indicate some of the possible modifications and elaborations of this idea.

In the drawings, Figure 1 is a diagrammatic view illustrating the mechanical arrangement of gearing and motors according to this invention. Fig. 2 is a diagram showing the electrical connections and the arrangement of the circuits. Fig. 3 illustrates a method of duplicating the arrangement illustrated in Fig. 1. Fig. 4 illustrates another method of duplicating the arrangement shown in Fig. 1. Fig. 5 is a diagram representing the electrical circuits for the arrangement illustrated in Fig. 4. Fig. 6 is a diagram illustrating the series switching of a number of motors arranged

on each shaft of a gearing. Fig. 7 is a diagram similar to Fig. 6 for the case in which the motor armatures are switched in parallel. Fig. 8 is a sectional elevation showing one form of carrying this invention into effect. Fig. 9 illustrates another arrangement suitable for the driving car of a train. Fig. 10 shows a form in which three motors are employed. Fig. 11 illustrates a form of the invention adapted for driving a ship's capstan by means of two motors.

According to the form shown in Fig. 1 two electric motors 1 and 10 are coupled by means of the gearing wheels 2 and 3. The wheel 3 is arranged on a shaft 5 which is or may be coupled to the shaft 6 carrying a pinion 7 arranged to drive the wheel 8 on the shaft 9. The coupling 4 between the two shafts 5 and 6 is preferably a magnetic coupling. It will be assumed in the following that the ratio of the maximum to the minimum speed for which the motors are wound is the same in both motors and is 5:1. This quantity will be referred to as the speed range. In this case the speed ratio of the gearing 2 and 3 would be 5:1 and the motor 1 would be the low speed motor.

The starting of the plant is effected as follows:—The motor 1 is started free in the usual way, for low loads without, and for greater loads with, a starting resistance. The arrangement may be such that the motor 1 is switched in when switching on to the main lines and runs at first with no load.

The circuit connections are illustrated in Fig. 2 in which 1 indicates the motor, *a* the starter, *r* the field controller and *f* the magnetic field. When starting, the magnetic field is most strongly excited and the speed of rotation of the motor 1 is its minimum. By means of the lever *h* the velocity of the motor may be increased by a multiple depending upon the type of the motor, for instance with an auxiliary pole motor it may be increased five fold. As can be seen in Fig. 1 the large motor 10 is set in motion by this mechanical coupling without being switched in.

The speed of the motor 1 which may be called the small motor although its size may be as great as that of the motor 10 may for instance be changed from n revolutions to $5n$ and the speed ratio of the wheels 2 and 3 is taken as 5:1. It will also be assumed that

the speed of the motor 10 when fully excited is

$$\frac{5n}{5}$$

5 (the denominator indicates the speed ratio of the gear) and when the field is least excited the speed of the motor will be taken as

$$\frac{25n}{5}$$

10 This assumption corresponds to the most frequent cases occurring in practice.

15 It is here again emphasized that the speed range of the motor should always be approximately the same as the speed ratio of the gear if the acceleration over the entire range is to take place without shock or material fluctuations. If the greatest velocity of the motor 1 has been reached and the 20 speed is to be further increased the following steps are taken:—The field F of the large motor 10 is first switched in and armature of the motor 10 is switched in without resistance. As the lower speed of the 25 motor is similar to the higher speed of the gear the motor 10 with normal current takes up motor 1 and performs one half of the work. The speed of the motor 10 may be gently increased (by regulating the field) from

$$\frac{5n}{5}$$

30 to

$$\frac{25n}{5}$$

35 The shafts 5 and 6 are connected by a clutch which may be uncoupled, in the case 40 illustrated in Fig. 1, a magnetic clutch 4 is assumed to be applied. In order that the small motor may not be required to rotate at a speed exceeding $5n$ the magnetic coupling is released. The small motor then 45 runs with no load at its highest speed $5n$ so that when passing from the larger motor 10 to the smaller, that is when reducing the speed, the transference from the larger motor to the smaller is also effected without 50 shock. By providing a magnetic coupling 4 the advantage is obtained that the motor 1 may be started with no load. As soon as 55 the electric motor 1 has reached the full (minimum) speed of rotation for which it is wound, the solenoid of the magnetic clutch 4 is energized and immediately the driving wheel 7 on the motor 10 starts to rotate at

$$\frac{n}{5}$$

60 revolutions per minute. If it is desired to reverse the rotation of the gear without stopping the small motor 1, a second coupling 4^a is employed and transmission gear,

11, 12 and 13 is provided as shown in lines in Fig. 1.

65 The manipulation of the switch, the starter and the magnetic clutch and the motion of both field controllers may be effected by a common switch arm. The switch for the main current may also be effected by other suitable means for controlling their positions from a distance *e. g.* by means of a contactor.

70 In ordinary cases two motors and one gear will be sufficient for a speed range of 1:25, a larger speed range may be obtained by either mechanical or electrical means.

75 In Fig. 3 there is illustrated an arrangement by which a greater speed range is obtained by mechanical means and this figure is an extension of the form of the invention 80 illustrated in Fig. 1. An electric motor 14 is directly or indirectly connected to the shaft 9 and the speed of rotation of this 85 motor may be varied between say

$$\frac{25n}{25}$$

90 and

$$\frac{125n}{25}$$

95 by controlling the field. The system illustrated in Fig. 3 is in other respects similar to that described with reference to Fig. 1. It will be understood of course that still further extensions may be made in a similar manner.

100 In Fig. 4 the method of obtaining a still greater speed range by electrical means is illustrated. In this case 1^a and 1^b denote two similar electric motors which are mechanically coupled. The two motors may also 105 be arranged otherwise. On the shaft of the motors 1^a and 1^b there is arranged a pinion 2 gearing with a toothed wheel 3 on the shaft 5 which is coupled to the shaft 6 by means of a magnetic clutch 4. The shaft 6 has two motors 10^a and 10^b mounted thereon and the pinion 7 on the shaft 6 gears with the toothed wheel 8 on the shaft 9. When starting with this arrangement, the motor 1^a is started with or without resistance 110 with no load while the clutch 4 is uncoupled.

115 The armature of the motor 1^b rotates with the motor 1^a and also runs with no load. The motor 1^a may be arranged for instance 120 for speeds between n and $5n$ and the motor 1^b for speeds between $5n$ and $25n$. By regulating the field in said motors therefore, the motor 1^a may be increased in speed up to 125 $5n$ which is also the minimum speed of the motor 1^b. When the motor 1^a reaches its maximum speed, the field of the motor 1^b is switched in and this motor then takes up half the work whereupon the armature of the motor 1^a is cut out and the motor 1^b 130

takes the whole load. The velocity of the motor 1^a may now be increased from $5n$ to $25n$ by regulating the field. The gear $2:3$ is in this case arranged to give a ratio of $5:25:1$.

The second pair of motors 10^a and 10^b are similarly arranged with the difference that this pair of motors may be started without a resistance. The magnetic clutch 4 again serves the same purpose as described with reference to Fig. 1. The arrangement described will thus give a speed range of $1:625$ if the separate stages have a speed ratio of $1:5$. It should be noted here that the voltage of the circuit may be constant and special dynamos with variable voltage, as in the Leonard system, may be dispensed with. The regulator switches may be operated by means of a switch arm with a hand wheel or the like and the entire system may be reversed electrically or by means of a special magnetic clutch. It will also be understood that two or more continuous or alternating current motors may be applied without any gear.

In Figs. 6 and 7 there are illustrated diagrammatically the methods of switching in the case in which several motors are arranged on each shaft. In Fig. 6 the arrangement is illustrated for switching the armatures in series and in Fig. 7 in parallel. The motors in the form illustrated are assumed to be shunt wound but the principle may also be applied for series motors. The series and parallel switching may also be combined so as to enable the transference from series to parallel switching. In each case eight main stages are assumed for a speed range of $n-5n$ and the other for $5n$ to $25n$. In the first stage a starting resistance is provided and both motors are fully energized when switching in series. The field of the slower motor is then reduced as far as may practically be effected and then the next speedier motor is employed in its range from complete to minimum field strength. During this time the first motor is, in the case of series switching, short-circuited and in the case of parallel switching is cut out.

In Fig. 6 it is assumed that the field of the quick running motor is reduced until the slow running motor has reached the speed at which it normally runs when fully energized, whereupon the speed of rotation of the small motor is increased by reducing the field until the speed of revolution is reached at which the quick running motor normally runs when fully energized. The small motor is then cut off and the same process continues with the high speed motor.

The method described of employing variable motors may also be extended to alternating and multi-phase motors for instance to motors of the Winter-Eichberg-

Latour type. For the sake of increasing the safety the magnetic or other clutch may be mechanically or electrically uncoupled by means of a centrifugal coupling so as to prevent the speed of the motor stages increasing beyond the permissible limit.

In Figs. 8, 9, 10 and 11 there are illustrated some practical embodiments of this invention. In Fig. 8, two motors m and m^1 are connected by a casing g . The motors are similarly wound and may be connected by a magnetic coupling k . When starting the disk h is connected to the toothed wheel r^4 . The motors are arranged in series so that both may develop the full power. The motor m^1 rotates more quickly than the motor m in the proportion of the intermediate gear r^1, r^2, r^3, r^4 and develops a correspondingly higher torque and as soon as the speed reaches the normal minimum of the motor m , when its field is fully energized, the magnetic clutch k is connected with the disk z . The motors are first of all connected in what might be called electrical and mechanical series and are then connected in parallel. When connected in parallel the speed of the motor m may be increased n fold by reducing the field.

According to the form shown in Fig. 9 a similar arrangement is illustrated which is suited for driving the car of a train. Both the motors m and m^1 , actuate a shaft v through the intermediate gear r^5 and r^6 . The motors m and m^1 may also be arranged on separate axes and the mechanical coupling may be obtained through the wheels of the car and the rails.

In Fig. 10 three motors are illustrated in a form suited for driving a capstan or gun setting mechanism. The motor m^1 starts the motor m^2 through a magnetic reversible coupling m^r and the motor m^2 starts the motor m^3 through the magnetic clutch m^k . If the speed ratio of the magnetic reversing clutch m^r is $1:7$ and the speed range of the motor m^3 is also $1:7$ and the two other motors have a speed ratio $1:6 1:5$ respectively the total speed ratio of the system is $1:120$. The speed of the motor m^3 may be varied from 7 to 1470 revolutions per minute. The application of a magnetic reversing clutch has the advantage that with the lowest velocities the direction of rotation may be easily and speedily reversed. In Fig. 11 there is illustrated a method of driving a ship's capstan by means of two motors. The motor m^1 and the motor m^2 are assumed as shunt motors and the armatures are arranged in series while the capstan is pulling. The motor m^2 is directly connected to the shaft s while the motor m^1 drives the same shaft through the gear r^1, r^2, r^3, r^4 and the magnetic coupling m^k .

As soon as the capstan starts, the motor m^2 is first cut out and runs with no load and

is only switched in with a starting resistance when the armature has reached its full speed (*i. e.* minimum limit) when the field is fully energized. Both motors then run in parallel but with different speeds. As soon as the motor m^1 exceeds its highest permissible speed the magnetic clutch m^k is deenergized and the motor m^2 rotates with no load. The motor m^2 then performs the work alone. In this way the speed of the capstan may be varied from 1:30 without employing any regulating resistances.

It will be seen that according to the present invention the rotary driven shaft is operated by a plurality of motors (m^1 and m^2 in Fig. 11) which are in mechanical series (through the gearing $r^1 r^2 r^3 r^4$), while the first motor m^1 in said series is coupled to the driven shaft s for the lower speed range of the said shaft. The second motor m^2 may then be operatively connected, through the clutch m^k to the shaft s for the succeeding (in this case the highest) speed range.

25 It will be understood that the forms of the invention described above are only taken as typical applications and do not by any means exhaust the uses to which the present invention may be applied.

30 I claim:—

1. In combination a rotary shaft, a plurality of electric motors for driving said shaft, intermediate gearing between said motors and said shaft, said motors being distributed on different shafts of said gearing and the speed ratio of the gearing between the motors corresponding substantially to the speed range of said motors.

2. In combination a rotary shaft, gearing through which said shaft is driven and means for controlling the speed of said shaft over a large range without shock comprising motors on different shafts of said gearing, the speed range of each of said motors being substantially equal to the speed ratio of the gearing arranged between it and the next and means for controlling the speed of said motors.

3. In combination, a rotary shaft, a plurality of gearing pairs in series and through which said shaft may be driven, shafts carrying said gearing pairs, electric driving means on one shaft of said gearing, the speed range of said driving means being substantially equal to the speed ratio of the

gearing between it and a further shaft in the series of gearing pairs and electric driving means on said further shaft.

4. In combination, a rotary shaft, a plurality of gearing pairs in series and through which said shaft is driven, shafts carrying said gearing pairs, a motor on one shaft of the gearing, the speed range of said motor being substantially equal to the speed ratio of the gearing between it and a further shaft of said gearing, a clutch between said motor driven shaft and said further shaft and a motor on said further shaft.

5. In combination, a rotary shaft, a plurality of gearing pairs in series and through which said shaft is driven, shafts carrying said gearing pairs, a motor on one shaft of the gearing, the speed range of said motor being substantially equal to the speed ratio of the gearing between it and a further shaft on said gearing, a magnetic clutch between said motor driven shaft and said further shaft.

6. In combination, a rotary shaft, a plurality of gearing pairs in series and through which said shaft is driven, a plurality of shafts carrying the members of said gearing pairs, a plurality of series arranged motors mechanically coupled and arranged to drive said gearing, one of said motors being arranged to drive its shafts through a speed range of approximately n to $5n$ and another being arranged to drive at speeds ranging from $5n$ to $25n$ whereby the variation in speed of the driven shaft may be effected.

7. In combination, a rotary shaft, gearing arranged to drive said shaft, shafts carrying said gearing, a plurality of motors on each shaft of said gearing, the collective speed range of said motors being substantially similar to the speed ratio of said intermediate gearing.

8. In combination, a rotary shaft, gearing arranged to drive said shaft, shafts carrying said gearing, double motors on each shaft of said gearing the speed range of said motors being substantially similar to the speed ratio of said intermediate gearing.

In testimony whereof I affix my signature in presence of two witnesses.

JOHN AUGUSTUS ESSBERGER.
